(57) **CLAIM**

The ornamental design for an audio speaker system, as shown and described.

DESCRIPTION

FIG. 1 is a front perspective view of an audio speaker system in accordance with the present invention;

FIG. 2 is a rear perspective view of an audio speaker system in accordance with the present invention;

FIG. 3 is a front view of an audio speaker system in accordance with the present invention;

FIG. 4 is a rear view of an audio speaker system in accordance with the present invention;

FIG. 5 is a right side view of an audio speaker system in accordance with the present invention;

FIG. 6 is a left side view of an audio speaker system in accordance with the present invention;

FIG. 7 is a top view of an audio speaker system in accordance with the present invention; and,

FIG. 8 is a bottom view of an audio speaker system in accordance with the present invention.

The broken lines shown are included for the purpose of illustrating portions of the audio speaker system that form no part of the claim.

1 Claim, 5 Drawing Sheets
